(12) **United States Design Patent** (10) **Patent No.:** **US D868,045 S**
(45) **Date of Patent:** **** Nov. 26, 2019**

(54) **ANTENNA**(71) Applicant: **Antennas Direct, Inc.**, Ellisville, MO
(US)(72) Inventors: **John Edwin Ross, III**, Moab, UT
(US); **Joanne Nosiglia**, Eureka, MO
(US)(***) Term: **15 Years**(21) Appl. No.: **29/672,540**(22) Filed: **Dec. 6, 2018****Related U.S. Application Data**

(63) Continuation-in-part of application No. 29/627,951, filed on Nov. 30, 2017, and a continuation-in-part of application No. 15/685,749, filed on Aug. 24, 2017, and a continuation-in-part of application No. 29/671,595, filed on Nov. 28, 2018, said application No. 29/627,951 is a continuation of application No. 29/580,049, filed on Oct. 5, 2016, now Pat. No. Des. 809,490, which is a continuation-in-part of application No. 14/308,422, filed on Jun. 18, 2014, now abandoned, and a continuation-in-part of application No. 29/430,632, filed on Aug. 28, 2012, now abandoned, which is a continuation-in-part of application No. 29/376,791, filed on Oct. 12, 2010, now Pat. No. Des. 666,178, said application No. 14/308,422 is a continuation-in-part of application No. 13/759,750, filed on Feb. 5, 2013, now Pat. No. 8,894,600, which is a continuation-in-part of application No. 12/606,636, filed on Oct. 27, 2009, now Pat. No. 8,368,607, which is a continuation-in-part of application No. 12/050,133, filed on Mar. 17, 2008, now Pat. No. 7,609,222, which is a continuation-in-part of application No. 29/304,423, filed on Feb. 29, 2008, now Pat. No. Des. 598,433, said application No. 12/606,636 is a continuation-in-part of application No. 12/040,464, filed on Feb. 29, 2008, now Pat. No. 7,839,347, said application No. 12/606,636 is a continuation-in-part of application No. 29/305,294, filed on Mar. 17, 2008,

now Pat. No. Des. 604,276, which is a continuation-in-part of application No. 12/040,464, filed on Feb. 29, 2008, now Pat. No. 7,839,347, and a continuation of application No. 12/050,133, filed on Mar. 17, 2008, now Pat. No. 7,609,222, said application No. 12/606,636 is a continuation-in-part of application No. PCT/US2008/061908, filed on Apr. 29, 2008, which is a continuation of application No. 12/050,133, filed on Mar. 17, 2008, now Pat. No. 7,609,222, and a continuation of application No. 12/040,464, filed on Feb. 29, 2008, now Pat. No. 7,839,347.

CLAIM

The ornamental designs for antenna, as shown and described.

DESCRIPTION

FIG. 1 is a perspective view of an antenna, showing our new design;

FIG. 2 is a back perspective view of the antenna shown in FIG. 1;

FIG. 3 is a front view of the antenna shown in FIG. 1;

FIG. 4 is a back view of the antenna shown in FIG. 1;

FIG. 5 is a right side view of the antenna shown in FIG. 1;

FIG. 6 is a left side view of the antenna shown in FIG. 1;

FIG. 7 is a top view of the antenna shown in FIG. 1; and,

FIG. 8 is a bottom view of the antenna shown in FIG. 1.

In the drawings, the details shown in broken lines depict environmental subject matter only and form no part of the claimed design.
